Fraser Clark Myers

UNITED STATES PATENT OFFICE.

ELMER McCLELLAN AFRICA, OF HUNTINGDON, PENNSYLVANIA, ASSIGNOR TO J. C. BLAIR COMPANY, OF HUNTINGDON, PENNSYLVANIA, A CORPORATION OF PENNSYLVANIA.

GUIDE-LINE SHEET.

1,340,100.

Specification of Letters Patent.

Patented May 11, 1920.

Application filed July 30, 1918. Serial No. 247,368.

To all whom it may concern:

Be it known that I, ELMER McCLELLAN AFRICA, a citizen of the United States of America, residing in the city and county 5 of Huntingdon and State of Pennsylvania, have invented certain new and useful Improvements in Guide-Line Sheets, of which the following is a specification.

My invention has to do with a guide line 10 sheet, to be used in connection with writing paper which is superposed upon the guide line sheet, while the lines of the latter are visible through the superposed writing sheet, and afford guiding means for writing uniformly upon an unruled paper.

The present invention is an improvement, 15 in part, upon Patent No. 14,488, reissued June 25, 1918, which included guiding instrumentalities consisting of alternately ar- 20 ranged light and dark bands of sufficient width to permit writing upon a superposed sheet within the spaces immediately above the bands, and this improvement is designed to carry out this same general purpose in a 25 more economical and practicable manner, while also making it easier to form lines of uniform height and size, thus possessing considerable advantage in the study or practice of penmanship.

More specifically, this feature of my invention consists in forming the dark bands 30 by means of a series of separate, spaced lines, which gives the desired effect of a sufficiently dark area in contrast with the 35 alternate light bands, and yet eliminates the solid dark field, such as forms a part of the structure of the patent above referred to. By the employment of individual, closely arranged lines, it is possible to effect a very 40 considerable saving in the ink used in printing the guide sheet, while the arrangement also prevents the paper from warping or wrinkling during the printing operation. A further advantage of the invention is that 45 the separate lines of the dark bands serve mechanically to aid in writing, by giving a ready means of determining the height and size of letters, thus making the structure of more educational value, while also adding 50 to its general appearance and commercial importance.

A further purpose of the invention is to afford a guide line sheet which can be used either with the usual flat sheet, or tablet 55 paper, or with the folded, or "note paper,"

and to make this possible, I employ guiding means, which may be in the form of bands, extending in both directions on the guide sheet, longitudinally and laterally, at right angles to each other. This arrangement 60 permits writing upon the superposed sheet either lengthwise or crosswise of the latter.

An additional object contemplated by the invention is to afford marginal indicating means, preferably in the form of heavier, 65 or darker lines, than the remaining lines of the sheet, and extending parallel to the edges at such a distance as to indicate the desired width of margin. These marginal lines may be disposed parallel to all the 70 edges of the sheet, so that margin indica- 75 tions are provided at the top, bottom and sides. Where a sheet of note paper is used, unfolded upon the guide sheet, it is desir- 80 able to provide margin indicating means upon opposite sides of the center of the note sheet, or—in other words—at the adjacent edges of the opposed or folded por- 85 tions, and this is attained by providing ad- ditional marginal lines of heavier or darker formation, extending crosswise of the guide sheet, on opposite sides thereof and parallel to its center line. If it be imagined that the guide sheet is folded crosswise along the center line, corresponding to the folding of 85 a superposed note sheet, it will be seen that inside margins are provided upon both folded portions of the note sheet.

To these ends, the invention consists in certain improvements and combinations of 90 parts as will be hereinafter more fully described, and pointed out in the claims at the end of the specification.

The drawing is a view in elevation illus- 95 trating a preferred embodiment of the dif- ferent features of my invention.

Referring to the drawing with greater particularity, it represents a sheet of card- 100 board or heavy paper of rectangular form, preferably of a length nearly double the width and with a white background or base. Arranged upon the background are wide dark bands A in parallel relationship and each of sufficient width to permit the superposed sheet of writing paper to receive writing within the space immediately 105 above the band. The bands A are formed by means of a series of separate lines a which are independent of each other, but arranged in sufficiently close relationship 110

to afford a dark area, as contrasted with the light bands B which are arranged alternately between the dark bands A, and are also of sufficient width to permit letters to be written upon a superposed sheet within the space immediately above a light band. The dark bands A are produced by ruling a series of fine lines, close to one another, and the effect obtained is just as desirable, for purposes of contrast with the light bands, as a solid dark area. With a solid dark area, the height of the letters must be obtained entirely from guesswork or approximation.

15 The guiding means above described permits writing in one direction, and in order to afford facility for writing in either direction with relation to the guide sheet, I employ additional guiding means extending at right angles to that previously referred to. Preferably, the supplementary guiding means is in the form of dark bands C and light bands D which are formed and arranged in the same manner as the bands 25 A and B. While this arrangement has been found to be a desirable and efficient one, it is not the only way in which the purpose of the invention may be carried out and I do not limit myself to this precise form, for 30 it is possible to substitute other specific kinds of guiding means for the bands as are hereinbefore set forth.

It is extremely desirable with my improvement, as well as with any guide sheet, 35 to indicate margins upon a superposed sheet in position for writing, and to this end I have provided marginal lines E extending parallel to the edges of the guide sheet in both directions, and spaced therefrom a distance corresponding to the width of margin desired. The marginal lines E are made darker or heavier than the remaining lines upon the sheet, so that they stand out with sufficient prominence to clearly indicate the 40 line of demarcation between the writing field and the marginal field, upon a superposed writing sheet. Where a "note sheet" or folded sheet is used for writing purposes, it is desirable to place it upon the guide sheet in unfolded arrangement, or perhaps to position only one portion of the folded sheet upon the guide sheet, with the other portion extending upon the reverse side of the guide sheet, merely as a matter of convenience, and to afford a proper margin entirely around the note sheet portion under such conditions. I utilize additional marginal lines F, also of darker or heavier character than said remaining lines on the sheet, 55 and of substantially the same degree of heaviness as the marginal lines E already referred to. The marginal lines F extend crosswise of the guide sheet in parallel relationship to its center line, and preferably 60 at equal distances therefrom, depending

upon the width of margin desired. Thus a marginal indication is afforded upon opposite sides of the center of the guide line sheet, when writing lengthwise.

While I have described the invention with reference to a particular form, I desire it understood that the improvement is not necessarily confined to this precise disclosure, and may be variously modified or changed without departing from the essential purposes of the invention, or the scope of the following claims.

What I claim is:—

1. A guide sheet for writing paper having a series of broad, dark bands thereon, each of which is composed of a series of separate lines, spaced slightly from each other, and a series of alternately arranged broad light bands, the dark bands being visible through a superposed sheet of paper when in position for use, and both the dark and light bands being of sufficient breadth to permit a superposed sheet to receive writing within the spaces immediately above either the dark or light bands. 90

2. A guide sheet according to claim 1, characterized by additional similarly formed dark and light bands extending at right angles to the first mentioned bands, so as to accommodate paper for writing in either 95 direction.

3. A guide sheet for writing paper having a series of spaced parallel guiding lines thereon, and additional spaced parallel guiding lines extending at right angles to the first-named guiding lines so as to accommodate paper positioned for writing either longitudinally or transversely, and characterized by marginal lines darker than the remaining lines and arranged in spaced parallel relationship to the edges of the sheet, so as to indicate margins on a superposed sheet of writing paper. 100

4. A guide sheet according to claim 3, characterized by additional marginal lines 110 darker than said remaining lines, and arranged crosswise on opposite sides of the center line of the sheet in spaced parallel relationship, so as to indicate central margins on opposite sides of the center of a 115 superposed unfolded sheet of double or "note paper."

5. A guide sheet according to claim 2, characterized by marginal lines darker than the remaining lines and arranged in spaced 120 parallel relationship to the edges of the sheet, so as to indicate margins on a superposed sheet of writing paper.

6. A guide sheet according to claim 5, characterized by additional marginal lines 125 darker than said remaining lines and arranged crosswise on opposite sides of the center line of the sheet in spaced parallel relationship so as to indicate central margins on opposite sides of the center of a 130

superposed unfolded sheet of double or "note paper."

7. A guide sheet for writing paper having a series of broad, dark bands thereon, 5 a series of alternately arranged broad light bands, and similar dark and light bands extending at right angles to the first mentioned bands, to accommodate paper for writing in either direction, the dark bands 10 being visible through a superposed sheet of paper when in position for use, and both said dark and light bands being of sufficient breadth to permit a superposed sheet to receive writing within the spaces immediately 15 above either the dark or light bands, said dark bands being each formed of a series of parallel lines.

8. A guide sheet according to claim 1, characterized by marginal lines darker than the remaining lines and arranged in spaced 20 parallel relationship to the edges of the sheet, so as to indicate margins on a superposed sheet of writing paper.

9. A guide sheet for writing paper having a series of spaced guiding lines thereon, 25 each formed of a series of parallel lines, and a marginal line darker than the guiding lines and arranged in spaced parallel relationship to each edge of the sheet, thereby forming rectangular margin-indicating 30 means.

In witness whereof, I have hereunto signed my name.

ELMER McCLELLAN AFRICA.
